UNITED STATES PATENT OFFICE.

BENJAMIN C. MATHES, OF ROCHESTER, NEW YORK.

CASTER.

No. 827,061.

Specification of Letters Patent.

Patented July 6, 1909.

Application filed January 12, 1909. Serial No. 471,928.

To all whom it may concern:

Be it known that I, BENJAMIN C. MATHES, of Rochester, in the county of Monroe and State of New York, have invented a new and useful Improvement in Casters, which improvement is fully set forth in the following specification and shown in the accompanying drawings.

This invention relates to certain new and useful improvements in casters of that general class shown and described in the Patent No. 888,040, dated May 19, 1908.

The present invention has for its objects among others to provide an improved caster of this general type, in which I provide means for stiffening and reinforcing the springs and for holding in place the upper free end of the central tube extending upward from the base.

Another object of the invention is to provide a simple and cheap, yet strong and efficient wheel formed in sections of sheet metal stamped or pressed into shape by means of dies and forms held in place by the member constituting the band or tire of the wheel.

I aim further at improvements in the details of the caster whereby the cost of manufacture is cheapened without lessening its practicability.

Other objects and advantages of the invention will hereinafter appear and the novel features thereof will be particularly pointed out by the appended claims.

The invention is capable of embodiment in a variety of forms, the most preferable of which are herein illustrated. The invention, in such preferred form, is clearly illustrated in the accompanying drawings, which, with the numerals of reference marked thereon, form a part of this specification, and in which—

Figure 1 is a side elevation of the improved caster with a portion of the axial tube broken away. Fig. 2 is an elevation of the caster looking at right angles to Fig. 1. Fig. 3 is a plan of the device viewed from above. Fig. 4 is an axial section of the wheel taken on the vertical dotted line 4—4 in Fig. 1, looking in the direction of the arrow. Fig. 5 is a plan view of the base ring detached, a portion of the inner ball-bearing plate or disk being broken away to show one of the balls and the cup holding the same. Fig. 6 is a plan of the upper portion of the device seen as in Fig. 3 with the hexagonal stiffening plate omitted. Fig. 7 is a vertical diametrical section of the upper parts of the caster, taken on the dotted

line 7—7 in Fig. 3, looking in the direction of the arrow. Fig. 8 is a side elevation of a modified form of the caster with parts broken away in central vertical section. Fig. 9 is a plan of the lower parts of the caster, showing the bearing groove for the upper parts. Fig. 10 is a plan of the under surface of the bearing plate of Fig. 8, showing the protuberances.

Like numerals of reference indicate like parts throughout the several views.

Referring to the drawings, and more particularly to Fig. 4, the construction of the wheel will be clearly understood. It is formed of two similarly cup-shaped parts 1, turned edge to edge with the lateral or flange portions 2, 2 abutting. These parts or sides 1, 1 are, by preference, given a curved form, as seen clearly in Fig. 4, both for the purpose of stiffening them and to give them a more ornamental appearance. They are made of sheet metal and may be stamped or pressed into shape by means of suitable dies and forms, or otherwise given the desired shape. At their centers they are formed with openings, and the edges 3, 3 of these openings are turned inward, as seen clearly in Fig. 4, for receiving the pin 5 which serves

as the axis upon which the wheel turns. 6 is a band or tire of metal surrounding the periphery of the two parts 1, 1 and has its edges spun downward and inwardly, as seen at 7, to partially inclose the parts or sides 1, 1 and firmly hold the same in position in a manner which will be apparent from Figs. 1 and 4. A wheel thus formed can be conveniently and cheaply constructed, is light, yet strong and durable, and, in practice, has proven to be very efficient. The pin or axle 5 is held in the jaws or side portions 8 of the vise, from the base 9 of which rises the spindle 10 which is of usual form except as hereinafter particularly pointed out.

The upper part of the device comprises a base plate 11 formed with downwardly pressed portions 12 for receiving bearing balls 13, as seen best in Fig. 7. These balls, at their upper sides, bear against the lower surface of a plate 14. Upon this plate rests the plate 15 which is hexagonal in form, as seen best in Fig. 6, having portions or flanges 16 which, with the plate 14, are held in position by the inwardly curved edge 17 of the base 11, as seen clearly in Figs. 6 and 7. Rising from this plate 15 are the springs 18 which are bent upon themselves at their up-

per ends, as at 19, their free ends depending downward and terminating at a point a short distance above the plate 15, as seen in Figs. 1, 2 and 7. As seen best in Fig. 6, 5 these springs rise from the plate at points between the flanges 16, the springs being unconfined by the inturned flange or rim of the base, but, at the junction of their inner sides with the base, strengthened and reinforced 10 by the inwardly pressed portions 20, as seen clearly in Figs. 6 and 7.

Rising centrally from the base 11 is an axial tube 21, seen best in Fig. 7, and at the upper end of this tube is a horizontal plate 15 15 22 which embraces said tube. Said plate is shown as hexagonal in form, every other side being formed with a tongue 23 engaged in openings in the inner vertical portions of the springs, as seen clearly in Figs. 3 and 7, 20 so as to stiffen and reinforce the springs near their upper ends and also to hold in place the upper free end of the tube. The upper end of the tube 21 is shown as provided with inwardly inclined projecting lips 24 which engage in a groove 25 in the upper end of the spindle or pin 10, so as to normally hold the same against displacement.

In Fig. 7, 26 designates the lower end of a hollow leg of a bed in which the coöperating 30 portion of the caster is shown as engaged, it being understood that the outer members of the springs are received therein and frictionally engaged with the inner surface of such hollow leg.

35 In Figs. 8, 9 and 10 I have shown a slightly modified form of my caster but embodying substantially the same principles and advantages, that is so far as pertains to the upper portion. In this form the wheel may be of a 40 construction similar to that hereinbefore described in connection with Fig. 4, or a wooden wheel or any other form suited to the purpose. In this form, however, in lieu of the balls 13, the plate 27 is formed with 45 downwardly extending protuberances 28 which rest at their lower ends in a circular groove 29, in the upper face of the base 9 of the yoke of the caster, the side portions 8 receiving the axle 5, the same as in the construction above described. The action and 50 result are substantially the same as in the form previously described.

Modifications in detail may be resorted to without departing from the spirit of the invention or sacrificing any of its advantages.

No claim is made in this application to the construction of the wheel *per se* as the same will form the subject-matter of a separate application to be filed as a division hereof.

What is claimed as new is:

1. In a caster, a plate, springs rising therefrom, and means adjacent the upper ends of the springs for stiffening and reinforcing the same.

2. In a caster, a plate, springs rising therefrom, and an axially supported plate near the upper ends of the springs having tongues received in openings in the inner members of the springs.

3. In a caster, a plate, springs rising therefrom, an axially supported plate near the upper ends of the springs having tongues received in openings in the inner members of the springs, and an axial tube received in and supported by said plate.

4. In a caster, a base having downwardly projecting parts, balls in said parts, a plate bearing on the upper surface of the balls, a plate resting on said plate and formed with spring arms bent upon themselves, the upper peripheral edge of the base being turned inward over said plates, and the springs reinforced at their junction with the plate.

5. In a caster, a base having downwardly projecting parts, balls in said parts, a plate bearing on the upper surface of the balls, a plate resting on said plate and formed with spring arms bent upon themselves, the upper peripheral edge of the base being turned inward over said plates, and the springs reinforced at their junction with the plate, and means for stiffening and reinforcing the upper ends of the springs.

6. In a caster, a base having downwardly projecting parts, balls in said parts, a plate bearing on the upper surface of the balls, a plate resting on said plate and formed with spring arms bent upon themselves, the upper peripheral edge of the base being turned inward over said plates, and the springs reinforced at their junction with the plate, means for stiffening and reinforcing the upper ends of the springs, and an axial tube rising from the base and received in and supported by said stiffening and reinforcing means.

7. In a caster, a wheel-supporting yoke, a base plate with axial tube, springs disposed about said tube, anti-friction bearings between said plate and the base of the yoke and means for stiffening the upper ends of said springs.

In witness whereof, I have hereunto set my hand this 8th day of January, 1909, in the presence of two subscribing witnesses.

BENJAMIN C. MATIUS.
